UNITED STATES PATENT OFFICE.

PETEE VOSS, OF ALLIANCE, OHIO, ASSIGNOR TO THE McCASKEY REGISTER COMPANY,
OF ALLIANCE, OHIO, A CORPORATION OF OHIO.

FILING APPLIANCE.

1,071,375.

Specification of Letters Patent. Patented Aug. 26, 1913.

Application filed January 2, 1912. Serial No. 663,934.

To all whom it may concern:

Be it known that I, PETER VOSS, a citizen of the United States, residing at Alliance in the county of Stark and State of Ohio, have invented certain new and useful Improvements in and Relating to Filing Appliances, of which the following is a specification.

This invention relates to a filing appliance or card index, or card system.

For the purpose of illustration, I have, in the accompanying drawing, shown and herein described one form of filing appliance embodying my invention, it being obvious that to those skilled in the art of filing appliances, many alterations in construction and application of my invention will suggest themselves without departing from the spirit and scope thereof.

Figure 1 is a longitudinal sectional view through a drawer or holder showing a series of cards and a follower embodying my invention. Fig. 2 is a rear elevation of the follower. Fig. 3 is a perspective view of the follower. Fig. 4 is a fragmentary view showing the application of a friction-increasing device to the drawer or holder.

In the drawing, 1 indicates a support or holder. It preferably comprises a drawer having a bottom 1^a, sides 1^b (only one side being shown), a front wall 1^c and a rear wall, which latter is not shown.

2 indicates the cards or papers which are filed in the holder 1, one behind the other and arranged on their lower edges as is customary in keeping records of any kind by a card system. The cards 2 may include suitable index, division or title-carrying cards, such as may be found necessary in the system.

3 indicates a follower mounted in the holder 1. It is movable or adjustable from end to end thereof in either direction to accommodate itself to the number of cards in the holder, or the increase or decrease in number thereof from time to time. The follower 3 comprises three members designated by the reference characters 3^a, 3^b and 3^c; the member 3^a serving to carry a portion of the cards and interposed between them and the bottom 1^a of the holder 1; the member 3^b operating as a back, abutment or rest for the rearmost card 2 and supporting it and the cards forward thereof in an ap-

proximately vertical position; and the member 3^c extending downwardly and rearwardly from the upper edge of the back 3^b and serving as a support therefor.

As shown in the drawing, the members 3^a, 3^b and 3^c may be formed from a single section of sheet metal that is bent on transverse lines 3^d, 3^e, to form them. Preferably, the angle between the bottom member 3^a and the back 3^b is slightly greater than a right angle in order that the cards 2 may be inclined rearwardly. The supporting member 3^c being somewhat longer than the back 3^b in a vertical direction, it maintains the bottom member 3^a at an angle to the bottom 1^a of the holder 1, so that said bottom member will engage or rest on the bottom 1^a along its forward edge only. By this construction it will be seen that the weight of the cards 2 on the bottom member 3^a will be carried by the forward edge of said member and the lower or free edge of the supporting member 3^c.

The supporting member 3^c is preferably provided with a series of teeth or projections 3^f the free ends of which may be sharpened or pointed in order that they may, under the influence of the weight of the cards, slightly penetrate the surface of the bottom 1^a and prevent the follower from slipping or sliding freely on the bottom. It will also be seen that as the supporting member 3^c is connected to the back 3^b along its upper edge, it is so disposed as to prevent the upsetting of the follower.

4 indicates friction-increasing devices, which may in some instances be used to prevent the sliding of the follower 3 longitudinally of the drawer or holder 1. These devices may comprise one or more plates fixed to the bottom 1^a. They extend substantially from end to end of the bottom and aline with the teeth or projections 3^f of the follower support 3^c. The upper surfaces of the devices 4 are roughened or serrated, as shown at 4^a, to form grooves in which the pointed ends of the teeth 3^f may be received.

As will be clearly understood from Fig. 4 of the drawing, the serrations 4^a will lock the follower against movement or adjustment longitudinally of the drawer, except when the follower is slightly elevated to raise the teeth above the serrations.

What I claim is:

1. A follower formed from a section of sheet metal and comprising a bottom member on which cards or papers are supported and a back for said cards extending upwardly from the rear edge of said bottom member, and a member for supporting said back, the said supporting member being connected with said back and arranged to support the bottom at an angle when the follower is mounted on a support.
2. The combination with a holder, of a follower formed from a section of sheet metal and comprising a bottom member on which cards or papers are supported, a back for said cards extending upwardly from the rear edge of said bottom member, and a supporting member extending downwardly from the upper edge of said back, the said supporting member being longer than said back, whereby the said follower is supported on the holder along the opposite transverse edges of the section of metal.
3. The combination with a holder, of a follower formed from a section of sheet metal and comprising a bottom member on which cards or papers are supported, a back for said cards extending upwardly from the rear edge of said bottom member, and a supporting member extending downwardly from the upper edge of said back, the said supporting member being longer than said back and provided on its free edge with a series of teeth for engaging the bottom of the holder.

In testimony whereof I affix my signature, in the presence of two witnesses.

PETER VOSS.

Witnesses:

R. MIDDLETON,

Disclaimer in Letters Patent No. 1,071,375.

DISCLAIMER.

1,071,375.—Peter Voss, Alliance, Ohio. FILING APPLIANCE. Patent dated August 26, 1913. Disclaimer filed November 30, 1914, by the assignee, *The McCaskey Register Company, (Incorporated in 1914.)*

Enters this disclaimer—

“To claim 1, which claim is in the following words, to wit:

“1. A follower formed from a section of sheet metal and comprising a bottom member on which cards or papers are supported and a back for said cards extending upwardly from the rear edge of said bottom member, and a member for supporting said back, the said supporting member being connected with said back and arranged to support the bottom at an angle when the follower is mounted on a support.”

[*Official Gazette, December 8, 1914.*]

What I claim is:

1. A follower formed from a section of sheet metal and comprising a bottom member on which cards or papers are supported and a back for said cards extending upwardly from the rear edge of said bottom member, and a member for supporting said back, the said supporting member being connected with said back and arranged to support the bottom at an angle when the follower is mounted on a support.
2. The combination with a holder, of a follower formed from a section of sheet metal and comprising a bottom member on which cards or papers are supported, a back for said cards extending upwardly from the rear edge of said bottom member, and a supporting member extending downwardly from the upper edge of said back, the said supporting member being longer than said back, whereby the said follower is supported on the holder along the opposite transverse edges of the section of metal.
3. The combination with a holder, of a follower formed from a section of sheet metal and comprising a bottom member on which cards or papers are supported, a back for said cards extending upwardly from the rear edge of said bottom member, and a supporting member extending downwardly from the upper edge of said back, the said supporting member being longer than said back and provided on its free edge with a series of teeth for engaging the bottom of the holder.

In testimony whereof I affix my signature, in the presence of two witnesses.
